(57) **CLAIM**

I claim the ornamental design for a support column dressing,
as shown and described.

DESCRIPTION

FIG. 1 is a perspective view of a support column dressing
according to the present invention.

FIG. 2 is a top view of the present invention. The bottom view
is the same.

FIG. 3 is a right side view of the present invention.

FIG. 4 is a front side view of the present invention.

FIG. 5 is a back side view of the present invention; and,

FIG. 6 is a left side view of the present invention.

The present invention is a new, original and ornamental
design for a support column dressing which surrounds and/or
is fitted onto a support column. The support column is not
claimed.

The broken lines are for illustrative purposes only and form
no part of the claimed design.
